UNITED STATES PATENT OFFICE.

HARRY R. ATWATER, OF CLEVELAND, OHIO, ASSIGNOR TO THE OSBORN MANUFACTURING COMPANY, OF CLEVELAND, OHIO, A CORPORATION OF OHIO.

MACHINE FOR JARRING MOLDS.

1,008,299.

Specification of Letters Patent. Patented Nov. 14, 1911.

Application filed May 19, 1910. Serial No. 562,166.

To all whom it may concern:

Be it known that I, HARRY R. ATWATER, a citizen of the United States, and a resident of Cleveland, county of Cuyahoga, and 5 State of Ohio, have invented a new and useful Improvement in Machines for Jarring Molds, of which the following is a specification, the principle of the invention being herein explained and the best mode in which 10 I have contemplated applying that principle, so as to distinguish it from other inventions.

The machine constituting the present invention may be regarded as an independent jolting stand, or as a filling stand adapted 15 for use with a rock-over or other similarly operative type of mold making machine, since the essential features of construction will be the same, irrespective of whether the machine be thus used as a plain jolt molding 20 machine or a rock-over jolt molding machine. The jolting stand form, presenting the simpler construction, has been chosen for illustration in the present connection.

The object of the invention is to provide 25 a machine of the character in hand that will be capable of giving any required length of stroke and any required compression under the blow, with any air pressure that will operate the machine.

To the accomplishment of these and related ends said invention then consists of the means hereinafter fully described and fully pointed out in the claims.

The annexed drawing and the following 35 description set forth in detail certain mechanism embodying the invention, such disclosed means constituting, however, but one of various mechanical forms in which the principle of the invention may be used.

In said annexed drawing:—Figure 1 is a side elevation of a jolting stand for a mold machine, embodying my several improvements; Fig. 2 is a plan view of a portion of said machine; and Fig. 3 is a central, vertical section taken on the line 3—3 Fig. 1.

Referring to the several drawings just described, the machine will be seen to comprise a tubular support A, wherein is reciprocably held a plunger A' that is provided 50 with a top α constituting the filling stand proper. It is to the latter, in other words, that the pattern plate holder (not shown) is attached when the apparatus is part of a rock-over mold making machine, and it is 55 also upon such top that the pattern and

flask are supported where the apparatus is used as a plain jolt machine.

In the position illustrated in Figs. 1 and 3 the plunger A' appears in its normal lower position of rest, from which however, it may be raised by the admission of compressed air or other equivalent pressure fluid through a suitable supply connection α' that enters the lower end of the tubular support. This supply connection will, of course, be controlled by a hand valve or other suitable controlling means at some convenient point on the supply line.

Leading from the opposite side of the tubular support is an exhaust passage α^2 connected with a muffler B, and controlled, when the mechanism is in operation, by a transversely disposed, reciprocable valve b in a casing B' secured to the outside of the tubular support. Said valve has a horizontally extending stem b' , to the outer end of which is connected one end of a bell-crank B² oscillatorily mounted in a bracket b^2 projecting from casing B'. Such bell-crank is provided with a rearwardly projecting weighted arm b^3 adapted to substantially, but not quite, counter-balance the other arm b^4 and parts carried thereby, as also to overcome any friction by which the movement of the valve may be restrained.

The other crank arm b^4 proper, is pivotally connected to an upwardly extending rod b^5 that freely slidably engages a bracket α^2 carried by the plunger A' of the machine (being affixed either directly to such plunger or to the under side of the head, which surrounds the same). Threaded on said rod, one above and the other below the bracket aforesaid, are two hand wheels b^6 b^7 that in effect form adjustably spaced stops, wherewith said bracket is adapted to engage upon reciprocation of the plunger, but with a certain amount of lost motion. These hand-wheels are adapted to be retained in desired position by means of a recurved leaf spring b^8 carried by the rod b^5 and adapted to engage notches provided in suitable number about the peripheries of said wheels, respectively. By variously adjusting the hand-wheels along the rod, it will be obvious that reciprocation of valve b to alternately open and close the exhaust α^2 from the tubular support A, may be secured at various points in the course of the upward and downward movement of the plunger A'. In other

words, by the control thus secured of the exhaust, a more or less rapid reciprocatory movement of the plunger will be produced, when air is turned on through the supply connection a' , and at the same time the length of the stroke of the plunger will depend upon the adjustment of the hand-wheel stops on the rod. It is contemplated that the air escape shall be shut off by the valve before the end of the down stroke, so that by the same adjustment of the lowermost of such stops, the volume of air confined within the support to deaden the jolt may be varied. A pin b^o determines the lower limit of adjustment for said stop.

In the lower end of the plunger there is mounted a head or tup a^4 of resistant material that is adapted to strike the bottom of the chamber within the support on said plunger's downward stroke, thereby producing the desired jarring effect. On the bottom of the chamber, moreover, there rests an annular block a^5 of wood or the like, which takes up the major portion of the annular space between the tup and the chamber walls in the lower position of such tup, thus in effect providing a recess that is adapted substantially to receive the latter and correspondingly diminish the volume of air required in the operation of the machine.

By reason of the horizontal disposition of the valve that controls the exhaust and the substantial balancing of the bell crank, as also of any frictional resistance to the movement of said valve, the latter is readily adapted to remain in whatever position it may be left and yet not require any particular effort to move the same. There is hence, no liability to disarrangement of the adjustment of the stroke, which, as has been explained, is controlled by adjusting the hand-wheel stops threaded on the rod b^5 . At some point in the upward stroke of the piston the bracket a^3 carried by the piston engages the handwheel b^7 which is fixedly secured to the sliding rod b^5 attached at its lower end to the bell-crank lever B^2 . The handwheel is thus raised, raising the rod and oscillating the bell-crank about its axis in the bracket b^2 thus closing the valve which is attached to the bell-crank. In this way the upper hand wheel can be made to close this valve, the inlet valve, at any desired point in the stroke by merely adjusting it at various levels. In a similar manner the exhaust valve may be closed by the action of the lower hand wheel in causing another movement of the bell-crank lever. Thus the exhaust valve is usually closed after a certain part of the down stroke, thus imprisoning some air in the chamber and slightly deadening the impact. Of such hand wheels, the upper it will be seen, determines the length of the stroke,

while the lower determines the amount of air confined at the conclusion of the stroke and thus the compression provided to deaden such stroke, the compression being increased by raising the lower wheel. By thus making stops in the form of wheels, no wrench is required to effect their adjustment, and at the same time owing to the accessibility of their position, such adjustment may be effected even while the machine is in operation. This is a very desirable feature for the reason that a number of trials would otherwise be required before exactly the desired result, in the way of jolting effect, could be secured.

The common practice, it will of course be understood, involves the use of the same machine to jolt molds of different weights, up to the maximum lifting capacity of the machine. Furthermore, a variation in the pressure of the air supply available for operation has to be considered. In view of these conditions the practical significance of the foregoing features will be more readily grasped.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a machine of the class described, the combination of a tubular support; a plunger reciprocable in said support and provided with a top, said plunger being adapted, on its down stroke, to strike the bottom of said support so as to jar an object on such top; fluid pressure supply and exhaust connections for said support; a valve controlling said exhaust connection; a rod disposed parallel with said plunger and connected to operate said valve; two peripherally notched hand wheels threaded on said rod; a spring borne by the latter and adapted to engage the notches in said wheels to retain the latter against rotation; and a bracket carried by said plunger and projecting between said wheels, whereby said plunger is adapted, during a part of its movement, to operate said valve.

2. In a machine of the class described, the combination of a vertically disposed tubular support; a plunger reciprocable in said support and provided with a top, said plunger being adapted, on its down stroke, to strike the bottom of said support so as to jar an object on such top; fluid pressure supply and exhaust connections for said support; a horizontally reciprocable valve controlling said exhaust connection; a bell-crank having one arm connected to reciprocate said valve; a rod disposed parallel with said

plunger and connected with the other arm of said bell-crank; and a bracket carried by said plunger and adapted, during a part of its movement, to engage and reciprocate said rod.

3. In a machine of the class described, the combination of a vertically disposed tubular support; a plunger reciprocable in said support and provided with a top, said plunger being adapted, on its down stroke, to strike the bottom of said support so as to jar an object on such top; fluid pressure supply and exhaust connections for said support; a horizontally reciprocable valve controlling said exhaust connection; a bell-crank having one arm connected to reciprocate said valve; a rod disposed parallel with said plunger and connected with the other arm of said bell-crank; and a bracket carried by said plunger and adapted, during a part of its movement, to engage and reciprocate said rod, said bell-crank being counter-weighted, substantially as described.

4. In a machine of the class described, the combination of a vertically disposed tubular support; a plunger reciprocable in said support, said plunger being provided with a top; a tup at the lower end of said plunger adapted to strike the bottom of said support on said plunger's down stroke; and an annular block on the bottom of said chamber arranged to leave a recess adapted to substantially receive said tup.

5. In a machine of the class described, the combination of a tubular support; a plunger reciprocable in said support and provided with a top, said plunger being adapted, on its down stroke, to strike the bottom of said support so as to jar an object on such top; fluid pressure supply and exhaust connec-

tions for said support; a valve controlling said exhaust connection; adjustable means connecting said valve with said plunger, but with lost motion, whereby said plunger is adapted, during a part of its movement, to variably operate said valve; and means limiting the range of adjustability of aforesaid means.

6. In a machine of the class described, the combination of a vertically disposed tubular support, a plunger reciprocable in said support, said plunger being provided with a top; a tup at the lower end of said plunger adapted to strike the bottom of said support on said plunger's down stroke; an annular block on the bottom of said chamber arranged to leave a recess adapted to substantially receive said tup; and means adapted to partially deaden the down stroke of said plunger.

7. In a machine of the class described, the combination of a vertically disposed tubular support; a plunger reciprocable in said support, said plunger being provided with a top; a tup at the lower end of said plunger adapted to strike the bottom of said support on said plunger's down stroke; an annular block on the bottom of said chamber arranged to leave a recess adapted to substantially receive said tup; and valves operated by said plunger and adapted to retain a certain amount of air in said tubular support during the down stroke of said plunger, whereby the force of the impact of said plunger on said bottom is lessened.

Signed by me this 17th day of May, 1910.
HARRY R. ATWATER.
